US0D1024151S

(12) **United States Design Patent** (10) **Patent No.:** **US D1,024,151 S**
(45) **Date of Patent:** **** Apr. 23, 2024**

(54) **CUTTING TOOL**

(71) Applicant: **SUMITOMO ELECTRIC HARDMETAL CORP.**, Itami (JP)

(72) Inventors: **Christoph Zeiner**, Willich (DE); **Makoto Abe**, Willich (DE); **Andreas Widmann**, Willich (DE)

(73) Assignee: **SUMITOMO ELECTRIC HARDMETAL CORP.**, Itami (JP)

(**) Term: **15 Years**

(21) Appl. No.: **29/763,101**

(22) Filed: **Dec. 21, 2020**

Related U.S. Application Data

(62) Division of application No. 29/682,820, filed on Mar. 8, 2019, now Pat. No. Des. 910,094.

(57) **CLAIM**

The ornamental design for a cutting tool, as shown and described.

DESCRIPTION

FIG. 1 is a front view of a cutting tool of the present design; FIG. 2 is a rear view thereof; FIG. 3 is a right side view thereof; FIG. 4 is a left side view thereof; FIG. 5 is an enlarged left side view of portion V of FIG. 4; FIG. 6 is a top view thereof; FIG. 7 is a bottom view thereof; FIG. 8 is a first perspective view thereof; and, FIG. 9 is a second perspective view thereof. The broken lines shown depict portions of the cutting tool that form no part of the claimed design. The dashed-dot-dashed lines depict a boundary of the enlarged portion and form no part of the claimed design.
